UNITED STATES PATENT OFFICE.

ROBERT P. TRAXLER, OF SAN FRANCISCO, CALIFORNIA.

RACING-HURDLE.

SPECIFICATION forming part of Letters Patent No. 732,680, dated June 30, 1903.

Application filed March 18, 1903. Serial No. 147,551. (No model.)

To all whom it may concern:

Be it known that I, ROBERT P. TRAXLER, a citizen of the United States, and a resident of the city and county of San Francisco and State of California, have invented a new and useful Improvement in Racing-Hurdles, of which the following is a specification.

This invention has for its object to provide for racing and athletic purposes a safety-hurdle having a rider or top piece that is capable of yielding and offering no material obstruction if struck by the feet of the horse or the person taking the hurdle and having also the quality of returning to position each time after being displaced.

To such end and object mainly my invention consists in certain novel construction and combination of parts, as hereinafter described, and pointed out in the claims at the end of this specification.

The accompanying drawings herein referred to represent in Figure 1 a perspective view of a hurdle embodying my invention. Fig. 2 is a rear elevation. Fig. 3 is a detail of the slip-joint employed to connect the frame of the yielding section to the stationary frame. Fig. 4 is a cross-section taken in a vertical plane.

The principal parts of my improved construction are herein designated for the purpose of description as the main frame *a*, the yielding top piece *b*, hinges *d*, and springs *e*. I prefer to make the main frame of the well-known triangular form, with braced legs *f* *g* set at proper distance apart to give stability and horizontal bars or panels *h* nailed across the front at intervals apart. To the rear side of this frame are attached, by hinges or pivots, one or more yielding top pieces, standing above the top rail of the frame and also extending from end to end of the hurdle, or approximately so. Generally I prefer to provide at least two of these top pieces to a hurdle where the same is of ordinary length; but for a long hurdle it is better to make the top piece in three or more separately-acting sections, not only for the reason that the shorter sections will yield more readily when struck and will return to position more quickly than a long section, but also to give a separate yielding top piece in the space or portion of the roadway occupied by each animal.

The preferable construction of this top

piece is seen in Figs. 2 and 3. A frame formed by bending stiff and heavy wire at right angles at the opposite ends to produce upright members *m* and a horizontal member *n* is attached to the back of the top rail by a pair of straps *p*, having sockets *s*, in which the horizontal member *n* is fitted to turn readily, and the central portion of the horizontal member lying between the hinges is bent downwardly or in the same plane with the upright arms *m* to form a rigid loop *n'*. To this loop is attached one end of a spring *e*, the other end of which is attached to a fixed point *w* on the main frame below the line of the hinges and somewhat to the rear of a vertical plane passing through them. Sufficient strain is applied by the spring thus connected to hold the hinged frame normally in an upright position, while the additional tension produced in the spring by turning the frame backward is sufficient to bring the frame to the upright position quickly against the resistance due to wind-pressure. A strip of woven fabric *2*, such as cotton cloth or canvas, stretched across the frame, is attached to the upright members *m* and to the bottom member in such manner that it can be taken off when the hurdle is out of service or when the cloth becomes worn or damaged. If white cloth be used for the covering, it may be left its natural color, or it can be given some contrasting color to enable it to be readily distinguished from the hurdle and the background against which it will be viewed by the racer. The object of using a woven fabric for the top piece is, first, for lightness, and, secondly, to offer less resistance to the air. I do not confine the construction of the covering to cloth alone, however, as other relative and open material, such as woven-wire fabric suitably colored to secure the desired contrast, could be used as well.

To facilitate the work of attaching and removing the top piece, I have provided a slip-socket to hold the wire frame, the construction of which is seen in the detail Fig. 4.

The strap *p* has an open loop *s* on the lower end of proper size to hold the rod *n* of the frame loosely, and over the open side of the loop, through which the rod is inserted and withdrawn, a swinging plate *3* is held by a set-screw *4*. By turning this plate to one

side the opening in the loop is uncovered, or by setting it in line with that opening and tightening the set-screw the rod is confined in the socket and at the same time is free to 5 turn loosely in it.

Having thus fully described my invention, what I claim as new therein, and desire to secure by Letters Patent, is—

1. A racing-hurdle comprising a stationary 10 frame of rails and posts, and yielding sections connected to the frame by hinges, and extending upward above the top of the frame, said sections consisting each of a yielding frame and a strip of textile material stretched 15 thereon, and springs attached to the stationary frame and to the yielding frame at a point below the axis of the hinges to hold the yielding sections normally in elevated position.

2. In a racing-hurdle, the combination of

a stationary frame of rails and posts; yielding sections attached to the top of said frame and standing above the top of said frame, said yielding sections comprising each a skeleton frame and a covering of material pervious to the wind; slip-hinges removably connecting the skeleton frame of each yielding section to the stationary frame, and springs connected to the skeleton frame and the stationary frame and adapted to retain the yielding sections normally in stationary position above 30 the top of the stationary frame.

In testimony whereof I have signed my name in the presence of two subscribing witnesses.

ROBERT P. TRAXLER.
